CLOSING MACHINE

Warren D. Jordan, Waukegan, and Henry W. Lindgren, McHenry, Ill., assignors to American Can Company, New York, N. Y., a corporation of New Jersey

Application January 9, 1942, Serial No. 426,230

10 Claims. (Cl. 226—82.4)

The instant invention relates to container or can closing machines and has particular reference to first locating a can to be closed on a lifter device and then shifting the can into closing position.

In the packing of whole hams and the like into cans, the usual procedure is to provide cans of different heights and to choose the height of can required for each individual ham so that the can will fit the ham. The cans vary in heights in increments of one-eighth of an inch over a range of probably one inch. Such a variety of cans thus creates some difficulty in closing them in the same machine, especially when the cans are of non-circular or irregular configuration in horizontal cross section.

The instant invention contemplates overcoming this difficulty by providing a semi-automatic machine having a multiple station turret with individually adjustable lifter devices for bringing the can and its cover to a predetermined level before entering a single closing station, the lifter devices being engageable at the closing station with mechanism for lifting the can into closing position.

An object therefore of the invention is the provision of a multiple station can closing machine wherein cans of different sizes may be received and located in respect to their heights on lifter devices which are individually engageable with actuating mechanism located at a single closing station for shifting the located cans into closing position.

Another object is the provision of such a machine wherein cans of irregular cross section may be properly located and retained against displacement while being brought into position for closing.

Numerous other objects and advantages of the invention will be apparent as it is better understood from the following description, which, taken in connection with the accompanying drawings, discloses a preferred embodiment thereof.

Referring to the drawings:

Figure 1 is a vertical sectional view of a can closing machine embodying the instant invention, with parts broken away;

Fig. 2 is a vertical sectional detail of a valve unit used in the machine, with parts broken away;

Figs. 3, 4 and 5 are horizontal sections taken substantially along the lines 3—3, 4—4 and 5—5 in Fig. 1, with parts broken away, Fig. 5 being drawn at an enlarged scale;

Fig. 6 is an enlarged horizontal sectional detail taken substantially along the horizontal line 6—6

in Fig. 1, with parts broken away, the view being revolved through ninety degrees and illustrating in dot and dash lines a different position of a movable part of the machine;

Fig. 7 is an enlarged fragmentary side elevation of the machine as viewed from the right in Fig. 1; and

Fig. 8 is a transverse vertical section taken substantially along the line 8—8 in Fig. 3, with parts broken away.

As a preferred embodiment of the invention the drawings illustrate a vacuum can closing machine for sealing covers A (Figs. 1 and 3) onto filled sheet metal cans B of irregular configuration after the cans have been vacuumized.

In such a machine the closing of a can B is effected preferably in the usual manner by a continuously rotating seaming head 11 (Fig. 1) having depending seaming rollers 12 and a chuck 13. The head is located in an open bottom seaming chamber 14 (see also Fig. 3) enclosed by walls of a frame 15 which latter constitutes the main frame of the machine. The head is mounted on a spindle within a sleeve 16 journaled in a pair of spaced bearings 17 formed in the machine frame.

The seaming head 11 is rotated by means of a pair of differential spur gears 21, 22 which are mounted on the spindle and on the sleeve 16, respectively. These gears are driven by meshing differential gears 23, 24 mounted on a vertical gear shaft 25 journaled in spaced bearings 26, formed in the machine frame. The gear shaft is driven by a belt 27 which operates over a driven pulley 28 mounted on the upper end of the gear shaft and over a driving pulley 29 mounted on a rotor shaft 31 of an electric motor 32 secured to the machine frame. The motor is the main source of power for operating the machine and this motor may be actuated from any suitable source of electric energy.

The covers A to be sealed to the cans B are inserted manually into a retaining ring 41 (Figs. 1 and 3) located in a rotatable turret or carrier

42. There are four of these rings and they are spaced equally apart adjacent the outer edge of the turret. Each ring is formed with a ledge 43 on which the cover rests. The rings are located over clearance openings or pockets 44 in the turret.

The top of the turret 42 is covered with a stationary plate 45 having an opening 46 through which a cover is inserted into a ring. This opening is disposed adjacent the sealing or seaming chamber 14 and constitutes a loading station at

which the operator of the machine stands. The plate is secured to a ring bracket 40 which is bolted to the machine frame.

The turret 42 is disposed in a horizontal position just below the closing head 11 so that a portion of the turret engages the bottom of the sealing chamber walls and thus closes off the chamber 14. This turret is bolted to a long depending hollow hub 47 which carries ball bearings 48 mounted on a stationary post 49 formed as a part of the machine frame.

Below each cover retaining ring 41 and in vertical alignment therewith is a lifter pad 52 (Figs. 1, 6 and 8) for supporting a can B to be closed. This lifter pad is formed on a vertical depending stem 53 which is carried in a sleeve 54. The sleeve is carried in a long bearing 55 formed on a hollow arm 56 which extends out from the turret hub 47. There are four of these arms, each carrying a lifter unit for each of the cover retaining rings 41 in the turret 42.

Each lifter sleeve 54 extends down below its bearing 55 and is formed at its bottom with a groove or notch 58 which sets off a hook 59. At its upper end, each sleeve is formed with a flange 61 which engages against the top of the bearing 55 and serves as a stop for holding the sleeve in the bearing. The sleeve flange merges into a dish shaped bracket 63 which extends up around the lifter pad 52 and terminates in a flat horizontal table 64 which is disposed substantially flush with the top of the lifter pad. There is one of these tables for each sleeve 54.

Each sleeve table 64 carries a pair of can half molds, i. e., a stationary mold 66 and a movable mold 67. The stationary mold is secured to the top of the table 64 while the movable mold is hingedly carried on a pintle 68 secured in hinge lugs 69 formed on both molds. The hinged mold may be swung open into the position shown in dot and dash lines in Fig. 6 and in this position a can B is inserted into the stationary mold. This insertion of the can and its cover is done manually at the loading station hereinbefore mentioned.

The upper edges of the molds 66, 67 are formed with inwardly projecting flanges 72 which are shaped to surround the irregular shaped can body when the molds are closed and thus hold the can in a predetermined position which is directly below and in vertical alignment with the cover A in the cover retaining ring 41. The inner edge of these holding flanges are grooved and carry a resilient cushion 73, made preferably of rubber, to tightly grip the can B to hold it in place.

When the molds are closed they may be locked in this position by a locking handle 75 which is carried on a pivot pin 76 secured in a lug 77 formed on the stationary mold 66. This handle is formed with a locking lug 78 which is engageable over a pin 79 in a lug 81 on the hinged mold 67, as best shown in Fig. 6.

A can B thus supported on the lifter pad 52 in a predetermined position and locked within the molds 66, 67, is raised vertically by the operator of the machine. This upward movement brings the top of the can into engagement with an indexing or locating plate 85 (see Figs. 3 and 8). This indexing plate is secured to the bottom of the ring bracket 40 and covers a space extending from the loading station to the sealing chamber. The plate locates the top edge of all cans regardless of their individual heights, in a predetermined position for the sealing operation. Such

operation follows at the closing station as will be hereinafter explained.

Raising of the can into engagement with the indexing or locating plate 85 is effected by a lever 86 (Figs. 1 and 7) mounted on a pivot pin 87 secured in a ratchet plate 88 which extends out from the sleeve 54. The inner end of the lever is formed with a ball shaped nose 89 which extends through slots 91 in the bearing 55 and in the sleeve 54 and operates in a slot 93 in the lifter pad stem 53.

The outer end of the lever 86 carries a rocker head 96 which is mounted on a pivot pin 97 secured in the lever. The rocker head is formed with a depending actuating handle 98 and a locking pawl 99. The pawl engages with ratchet teeth 101 formed on the outer edge of the ratchet plate 88 and is held against the teeth by a compression spring 102 interposed between the rocker head and the top edge of the lever.

Hence by gripping the handle 98 and pressing it inwardly, the operator of the machine may withdraw the locking pawl 99 from the ratchet teeth 101 and thus shift the lever 86 in the proper direction to raise or lower the lifter pad 52. When a can B on the lifter pad has been located against the locating plate 85, the operator releases the handle 98 and this permits the spring 102 to return the locking pawl 99 into locking engagement with the ratchet teeth 101. The lifter pad with the can thereon, is thus locked against displacement in the proper position for subsequent operations.

With the can B thus positioned as to height and held in place by the half molds 66, 67, the turret is rotated through a quarter turn or ninety degrees to shift the can and its cover, held in spaced relation thereto in the retaining ring 41, from the loading station to the closing station. Rotation of the turret is effected by a pair of meshing intermittent gears 111, 112, (Figs. 1 and 3). Gear 111 is formed on the bottom of the turret 42. The gear 112 constitutes a driving gear and is fixedly mounted on a vertical actuating shaft 113 carried in bearings 114 formed in the machine frame.

The actuating shaft 113 is rotated through a single revolution clutch which includes a clutch gear 116 (Figs. 1 and 5). This gear is loose on the actuating shaft 113 and meshes with a pinion 117 formed on the differential gear shaft 25. Thus the clutch gear is rotated continuously in time with the seaming head 11. The clutch gear is formed with a hub 118 having a notch 119 in its inside surface. This hub extends up around a collar 125 which is keyed to the actuating shaft 113. The collar carries a pawl 126 backed up by a spring barrel 127 located in a bore 128 formed in the collar.

The pawl 126 normally is held in a recess 129 located in the collar, by a trip arm 132 which engages against the side of the pawl. The trip arm is mounted on a shaft 133 carried in bearings 134 formed in the machine frame adjacent the clutch gear. The shaft extends exteriorly of the frame and carries a trip handle 135.

Thus when it is desired to rotate the turret 42 it is merely necessary to press down on the trip handle 135. This action lifts the inner end of the trip arm 132 out of engagement with the pawl 126 and thus permits the spring barrel 127 to press the pawl outwardly against the inside surface of the clutch hub 118.

When the notch 119 in the rotating hub moves adjacent the pawl, the latter snaps into the

notch and thus locks the collar 125 and the clutch hub 118 together. The clutch gear is thus temporarily fastened to the actuating shaft 113 and rotates this actuating shaft through one revolution. It is this rotation of the shaft that revolves the turret 42 through the quarter turn hereinbefore mentioned.

At the termination of one revolution, the actuating shaft 113 comes to rest. Stopping of the actuating shaft is brought about by a cam 141 (Fig. 1) which is mounted on the shaft above the clutch members. This cam bears down on the raised trip arm 132 and thus depresses it into a position where its inner end is in the path of travel of the clutch pawl 126.

Hence as the rotation clutch gear 116 brings the pawl into engagement with the trip arm, the latter forces the pawl inwardly into its recess 129 in the collar 125 and thus releases the pawl from its driving notch 119 in the gear hub. It is this release that disconnects the continuously rotating clutch gear 116 from the actuating shaft and thus brings the latter to rest.

During the rotation of the actuating shaft 113, the lifter sleeve 54 is raised to lift the can and its cover up into engagement with the closing head 11 located at the closing station. This is effected by a lifter lever 145 (Figs. 1 and 4) which is located near the bottom of the machine. The arm is mounted on a pivot pin 146 which is threaded into a boss 147 on the machine frame. The outer end of the arm carries a cam roller which operates in a cam groove 148 of a barrel cam 149 mounted on the actuating shaft 113.

The inner end of the lifter arm 145 is formed with a pair of fork arms 153 which are connected to links 154 mounted on pivot pins 155 secured in a collar 156 on a reduced shouldered portion 157 of a lifter actuating rod 158. The rod is disposed in a vertical position at the closing station and is slidably located in a long bearing 159 formed in the machine frame. A compression spring 162 interposed between the rod and the collar 156 thereon, provides for a yieldable connection between the rod and its actuating lever 145. The upper end of the rod is formed with a notch 164 and a hook 165 which are complementary to the slots or notches 58 and hooks 59 of the lifter sleeves 54.

When the turret rotates to shift a can and its cover from the loading station to the closing station, the lifter sleeve 54 at the loading station shifts with the turret toward the lifter actuating rod 158 and the slot 58 and hook 59 mesh with or engage with the notch 164 and hook 165 of the actuating rod. Before the actuating shaft 113 comes to rest, the cam 149 and actuating lever 145 raise the lifter actuating rod 158 and thus lift the table 64, molds 66, 67, lifter pad 52 and can B, as a unit. During this lifting action the molds move up into the clearance space 44 or turret pocket and into engagement with the inner wall of the latter (Fig. 1), below the cover retaining ring 41 in the turret 42 and thus block off the outside atmosphere, thus constituting a substantially hermetic fit with the ring.

The cycle of operation of the machine is such that the one revolution clutch stops the actuating shaft 113 and the lifter cam 149 carried thereon, just as the rising can B engages the cover A located in the corresponding retaining ring 41. The can and the cover come to rest at the closing station and in vertical alignment with the closing head 11, as best shown in Fig. 1. The

turret 42 also comes to rest and is locked against movement by the locking section of the driving gear 112 (Fig. 3).

5 While the turret 42 and the can B are thus at rest, the sealing chamber 14 (with its bottom blocked off by the molds 66, 67) and the can are vacuumized to remove the air from the can. Vacuumizing of the sealing chamber is brought about by way of a pipe 171 (Figs. 1 and 2), which leads from any suitable source of vacuum. The machine end of the pipe is threaded into a horizontal bore 172 of a valve block 173 formed on a wall of the sealing chamber. The bore 172 leads 10 into the chamber.

15. The valve block 173 carries a vertical slide valve 174 disposed in a bore 175 that extends across and normally closes off the horizontal bore 172. Intermediate its ends the slide valve is relieved to form a space between the valve and the valve block surrounding the valve. The ends of the valve extend beyond the valve block where they are engageable with a pair of spaced cams 178, 179 formed on a hub 181. This hub is mounted on and rotates with the actuating shaft 113, and is located between the two intermediate bearings 114.
- 20.
- 25.

Thus just before the actuating shaft 143 comes to rest at the completion of a cycle, the upper cam 178 engages the adjacent end of the slide valve 174 and forces it down in its bore 175. This movement of the slide valve closes off an atmosphere port 182 in the slide block and simultaneously opens the vacuum bore 172, as best shown in Fig. 2. This opening of the vacuum bore 172 brings the sealing chamber 14 into communication with the source of vacuum to exhaust the air from the can as hereinbefore mentioned.

This vacuum is drawn on the sealing chamber and can for as long as the turret 42 remains at rest. During this time the operator of the machine removes a sealed can from the molds now at the loading station and inserts a new unsealed can and a cover. This is done manually. The one or single revolution clutch then is tripped manually by operation of the clutch handle 435, as hereinbefore mentioned. Tripping of the clutch starts the machine cycle, as now will be explained.

As soon as the clutch is tripped, the actuating shaft 113 with the intermittent gear 111 and the cam 149 begin to rotate. The turret 42 is thus moved substantially 90° to and temporarily remains at rest at the closing position directly beneath the seaming head 11 (Figs. 1 and 3). While the turret is at rest in this immediately subsequent position, the cam 149 raises the lifter unit engaged with the lifter rod 158. This moves the can up through the cover retaining ring 41 and picks up the cover from the ring. As the can and cover continue to move up with the lifter unit, the cover comes into engagement with the seaming head chuck 13 and the seaming of the cover onto the can takes place by the operation of the seaming rollers 12.

er
65 After the can is sealed, it is moved down to
k a its original position through the cover retaining
a h ring, by the lowering of the lifter unit. Simul-
t- taneously with this action the vacuum is broken
ed in the sealing chamber 14. This is brought about
70 by the lower valve cam 179 on the rotating actu-
ating shaft 113. The cam engages the lower end
the of the slide valve 174 in the valve block 173 and
at pushes the valve upwardly. This closes the
ch 75 vacuum bore 172 and thus cuts off the chamber
the from the source of vacuum. The valve also

simultaneously opens the atmosphere port 182 to admit air into the chamber. It is this air that breaks the vacuum.

When the lifter unit reaches its lowermost level, the teeth on the intermittent driving gear 112 engage with the teeth on its mating gear 111 and rotate both the gear and the turret 42 through a ninety degree stepped rotation. This movement advances the closed can into the following idle station and brings the unsealed can and cover from the loading station into the closing station. This rotation of the turret disengages the lifter sleeve 54 of the lifter unit bearing the sealed can, from the lifter actuating rod 158 and brings the sleeve of the newly loaded lifter unit into engagement with the actuating rod. The gear 111 and turret then come to rest at their newly indexed position while the actuating shaft 113 and gear 112 continue to rotate.

Further rotation of the actuating shaft 113 continues to rotate the lifter cam 149 and this cam then raises the lifter actuating rod 158 and the newly engaged lifter unit and moves the unsealed can B up into engagement with its cover A in the cover retaining ring 41. It also operates the slide valve 174 to open again the vacuum bore 172 to re-vacuumize the sealing chamber. At this point in the machine cycle the clutch is disengaged from the actuating shaft 113 and the shaft and the parts connected therewith cease rotation. This completes the machine cycle.

The following is a brief summary of the operation of the machine:

An operator standing at the loading station in advance of the seaming chamber (Figures 3, 6 and 8) manually inserts a cover A through opening 46, and drops it onto ledge 43 of the turret 42. He also opens the half molds 66, 67 and places a can on the lifter plate 52, raises the lifter plate by actuation of a lever 86 associated therewith until the top of the can touches plate 85 (Figure 8) thereby locating or indexing the can top at a height predetermined for efficient operation at a subsequent station. The half molds are then closed and locked and trip handle 135 (Figure 5) is depressed to set the machine in motion for one cycle during which the turret 42 rotates through 90 degrees bringing the can and its cover above it into vertical alignment with seaming head 11.

Before the turret comes to rest, however, slot 58 and hook 59 of turret sleeve 54 mesh or engage with complementary hook 165 and notch 164 of rod 158 which, actuated by cam 149 through lever 145, raises the lifter pad 52 and the can held thereon. The can is raised until it reaches the position shown in Figure 1, assembled with its cover A. Simultaneously, the upper periphery of the closed molds 66, 67 enters and forms a substantially hermetic seal with the inner surface of its turret pocket 44.

Vacuum slide valve 174 (Figures 1 and 2) is automatically opened just before the end of the cycle and remains open to effect the vacuumization of the can and its contents while the operator unloads and loads the next turret ring and molds.

When the operator again trips the clutch handle 135, the turret 42 remains at rest for a short time while cam 149 through lever 145 and rod 158 raises the can and assembled cover still higher and into operating position with the seaming head 11. When the seaming operation is completed, the sealed container is moved downwardly by cam 149 to its lowermost position and the turret is rotated through another 90 degrees.

The closed cans are moved through two idle stations (Figure 3) before they reach the operator at the loading station unless a second operator is placed at one of the idle stations to remove them by opening the half molds 66, 67 (Figure 6).

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a can closing machine, the combination of a housing enclosing a chamber and having an opening therein for receiving cans to be closed, means for vacuumizing said chamber, a closing head located within said chamber, a turret for sealing the opening in said chamber, said turret being rotatable through a plurality of working stations and having spaced pockets alignable with said closing head, a plurality of lifter devices located one adjacent each of said turret pockets and rotating with the turret for carrying cans to be closed, lifter actuating means disposed adjacent said chamber and engageable with each of said lifter devices as it moves adjacent said actuating means during rotation of said turret to shift the said lifter device and the can carried thereon into the closing head for the closing operation, and a pair of half molds mounted on each lifter device and adapted to be moved into the turret pockets for hermetically sealing the latter against entrance of air thereto and into said chamber and for locating and holding a can in a predetermined position during the closing operation.

2. In a can closing machine, the combination of a can closing head, a turret disposed adjacent said head and rotatable through a plurality of working stations, a plurality of lifter devices disposed adjacent said turret and rotating therewith for supporting cans to be closed, each of said lifter devices including a vertically movable table, a hollow depending stem formed on each table, a lifter pad for each table, said pads being independently movable relative to said tables, a pad stem formed on each of said pads and carried in the hollow stems of said tables, operating means connected with each pad stem for manually shifting the pad vertically to bring the upper edge of a can placed on the pad into a predetermined elevation above its table, a locking device associated with each of said operating means for locking a located can and its lifter pad in said elevated position, and lifter actuating means disposed at a single station adjacent said closing head and engageable by each of the hollow stems of said tables for further shifting each lifter device with its lifter pad in the above mentioned locked position to bring the can carried thereon into engagement with the closing head for the can closing operation.

3. In a can closing machine, the combination of a housing hermetically sealed with the exception of an opening formed in the lower portion thereof, a flat continuous sealing flange on the exterior of said housing surrounding said opening, a seaming head in said housing adjacent said opening, an intermittently movable carrier having an upper flat sealing surface adapted to contact said housing flange in a substantially hermetic sealing engagement, a series of can and

cover assembling units in said carrier movable into vertical alignment with said head and said opening, each of said units comprising a can-holding mold having a continuous peripheral flange, a cover-holding ring in said carrier in vertical alignment with said mold, a sealing pocket formed in said unit adjacent said ring, said pocket being adapted to engage the flange of said mold in a substantially hermetic seal, means for moving said parts into and out of the above mentioned hermetic sealing relations with each other, means for creating a partial vacuum in said housing and unit when thus sealed, and means for assembling a can and cover and for actuating said seaming head to unite said cover and can in said partially vacuumized housing and unit.

4. In a can closing machine, the combination of a housing hermetically sealed with the exception of an opening formed in the lower portion thereof, a flat continuous sealing flange on the exterior of said housing surrounding said opening, a seaming head in said housing adjacent said opening, an intermittently rotatable turret having an upper flat sealing surface adapted to contact said housing flange in a substantially hermetic sealing engagement, a series of can and cover assembling units in said turret movable into vertical alignment with said head and said opening, each of said units comprising a can-holding mold having a continuous peripheral flange, a cover-holding ring in said turret in vertical alignment with said mold, a sealing pocket formed in said unit adjacent said ring, said pocket being adapted to engage the flange of said mold in a substantially hermetic seal, means for moving said parts into and out of the above mentioned hermetic sealing relations with each other, means for creating a partial vacuum in said housing and unit when thus sealed, and means for assembling a can and cover and for actuating said seaming head to unite said cover and can in said partially vacuumized housing and unit.

5. In a can closing machine, the combination of a can closing head, a turret disposed adjacent said head, said turret being rotatable through a plurality of working stations, a plurality of lifter devices rotatable with said turret for supporting cans of different heights to be closed, a stop plate disposed adjacent said turret for definitely locating the upper edges of said different height cans at a predetermined elevation relative to the seaming plane of said closing head, means carried by each lifter device for partially elevating a can into engagement with said stop plate to definitely locate the upper edge of the can irrespective of its height, and lifter device actuating means adapted to be engaged by said lifter devices for raising the latter as the same individually move into position adjacent said closing head to further elevate the pre-located cans on said lifter devices into sealing position in the closing head irrespective of the height of the cans.

6. In a can closing machine, the combination of a can closing head, a turret disposed adjacent said head, said turret being intermittently rotatable through a plurality of working stations and having circumferentially spaced pockets for holding can covers in vertically spaced relation to the cans to be closed, a plurality of lifter devices disposed adjacent said pockets on said turret and rotatable with the turret for supporting cans of different heights to be closed, manually actuated means carried by each lifter device to raise

the top of each can to a predetermined level relative to its can cover irrespective of the height of the can, lifter device actuating means having removable interlocking engagement with said lifter devices as the latter individually move adjacent said closing head to elevate each lifter device and the can carried thereon to pick up the cover and to move the assembled can and cover into the closing head for the closing operation when said turret is at rest, and actuating means for rotating said turret and for operating said lifter device actuating means in timed relation.

7. In a can closing machine, the combination of a turret rotatable through a loading station and thence through a closing station having a closing head, said turret having circumferentially spaced open ended pockets for holding can covers in vertically spaced aligned relation to the cans to be closed, a plurality of lifter devices carried by said turret for supporting said cans, means at said loading station for partially elevating a said lifter device and a supported can toward its vertically aligned cover, means for limiting upward movement of said partially elevated can at a fixed distance below and relative to said closing head, means on a said lifter device movable into engagement with said partially elevated supported can to surround the same at said loading station, lifter device actuating means disposed adjacent said stations and having means thereon for removably engaging each lifter device in succession as the latter are advanced from said loading station to further elevate a said lifter device and the can and its cover into a said turret pocket for a closing operation on the can, the said further elevation of said can engaging said can surrounding means with said turret pocket to seal off the can from the atmosphere during the closing operation, and means for advancing said can and its said aligned cover from said loading station to said closing station.

8. In a can closing machine, the combination of a can closing head, a turret disposed adjacent said head and rotatable through a loading station and thence through a closing station, said turret having circumferentially spaced open ended pockets for holding can covers in vertically spaced aligned relation to the cans to be closed, a plurality of lifter devices carried by said turret for supporting the cans to be closed, means at said loading station for partially elevating a said lifter device and a supported can towards its vertically aligned cover, means for limiting upward movement of said partially elevated can at a fixed distance below and relative to said closing head, means on a said lifter device rotatable with said turret and movable into engagement with said partially elevated supported can to surround the same at said loading station, lifter device actuating means disposed adjacent said closing station beneath the closing head and having means thereon for removably engaging each lifter device in succession as the latter are advanced from said loading station to further elevate a said lifter device and the can and cover carried thereon to engage the can and its cover with said closing head for the closing operation on the can, the said further elevation of said can engaging said can surrounding means with said turret pocket to seal off the can from the atmosphere during the closing operation, and means for advancing said can and its said aligned cover from the loading station to said closing station.

9. In a can closing machine, the combination

of a can closing head, a turret disposed adjacent said head and rotatable through a loading station and thence through a closing station, said turret having peripherally spaced open ended can receiving turret pockets therein, a plurality of can lifter devices rotatable with said turret for supporting cans of varying heights to be closed, means carried by said turret adjacent a said pocket thereof for partially elevating a can on a said lifter device to accommodate the height of the can received thereon, means cooperating with said elevating means to locate the open end of the can relative to its said turret pocket at a predetermined elevation below the seaming plane of said closing head, means on said lifter device movable into engagement with said partially elevated supported can to surround said can at said loading station, and lifter device actuating means disposed adjacent one of said stations and having means thereon adapted to removably engage each of said lifter devices as the same move adjacent thereto for raising a said lifter device to further elevate the can thereon into its said turret pocket and into sealing position in the seaming plane of said closing head at said closing station, the said further elevation of said can engaging said can surrounding means with said turret pocket to seal off the can from the atmosphere during the closing operation.

10. In a can closing machine, the combination of a can closing head, a turret disposed adjacent said head and intermittently rotatable through a loading station and thence through a closing

station, said turret having circumferentially spaced open ended pockets for receiving cans to be closed and for holding can covers in vertically spaced aligned relation to said cans, a plurality of can lifter devices rotatable with said turret for supporting cans to be closed, manually actuated means carried by said turret adjacent a said pocket thereof for partially elevating cans on said lifter devices to raise the open upper end of each can to a predetermined level relative to its said turret pocket, means on a said lifter device movable into engagement with a supported can thereon to seal off the can in vertically spaced relation to its said turret pocket, lifter device actuating means disposed adjacent said closing station beneath said closing head and having means thereon for removably engaging each of said lifter devices as the latter are successively advanced adjacent thereto to further elevate each lifter device and the can and cover carried thereon into the closing head for the closing operation when said turret is at rest, means for rotating said turret from said loading station to said closing station, and means for operating said lifter device actuating means in timed relation to the rotation of said turret, the said further elevation of said can engaging said can surrounding means with said turret pocket to seal off the can from the atmosphere during the closing operation.
